RAILWAY ROADBED

Pete Jarnowski, Chicago, Ill.

Application February 1, 1938, Serial No. 188,120

10 Claims. (Cl. 238—7)

My invention relates to railway roadbeds, and one of my objects is to provide a roadbed which not only forms a track support, but also combines a vehicular highway with a roadbed.

5 A further object of the invention is to provide a roadbed which can be produced in sections and laid in a suitable foundation in the course of the railway.

10 A still further object of the invention is to provide a roadbed which furnishes a depressed support for the rails, in order to have the same flush with the surface of the road.

15 Another object of the invention is to provide a filler unit between the rails and to so set the same in the foundation that lateral departure or creeping of the rails will be impossible.

20 An additional object of the invention is to provide a simple and unique means for uniting the sections of the roadbed.

25 With the above objects in view and with any others that may suggest themselves from the description to follow, a better understanding of the invention may be had by reference to the accompanying drawing, in which:—

Fig. 1 is a perspective view of the novel roadbed, partly broken away;

Fig. 2 is an enlarged cross-section; and

Fig. 3 is a fragmental plan view.

Railway roadbeds were primarily built exclusively for railroad traffic and in a manner peculiar to the immediate need or function rather than with a view to development. Thus, no other traffic can be accommodated; also, the existing equipment does not afford sufficient protection against the spreading or other dislocation of the rails from heavy traffic or weather conditions. It has therefore been my intention to provide a roadbed which is modernized to accommodate any kind of traffic, as well as to maintain the rails in proper position and relation at all times.

In accordance with the foregoing, the concrete roadbed is fabricated in slabs, as indicated at 10, and these are formed at the ends with a step 10a on the under side. The steps of adjoining slabs are laid over concrete cross-members 11 of oblong cross-section, such cross-members having upward projections 11a at the ends to abut the sides of the roadbed joint. When the joint is made, a filling of cement or mortar is interposed between its constituents so that when the joint is completed it is of an integral nature.

Along the course of each railroad track, the roadbed is cut down longitudinally, as indicated at 10b, to accommodate each rail. The cavity created by two such depressions has a short inward

shelf 10c at each side, and a bottom 10d stepped down between the shelves.

The sides 10b of the track cavity are adapted to receive the head 12 of the corresponding rail 13 in abutting relation; also, such side is made with a deep lateral groove 10e to accommodate a portion of one of the base flanges 14 of the rail 13, as shown in Fig. 2, the rail resting on the corresponding shelf 10c.

10 The bottom 10d serves to accommodate a longitudinal series of slabs 15 also made of concrete and closely fitted between the shelves 10c. However, in the terminal corners of each slab are bottom cavities 15a which afford clearance for the application of securing means for the rails 13 15 before the slabs 15 are laid.

15 Each of the securing means just referred to comprises a clamping plate 16 applied over the free base flange of the rail and extended downwardly with a base portion 17 resting on the roadbed bottom 10d. Bolts 18 are applied by way of the base portion 17 to secure the latter to the roadbed; and the cavities for the bolts are supplemented by larger ones for expanding sleeves 19 carried by the bolts and operating to lock the same to the roadbed when the fastening has been completed. This form of fastening is provided and has been shown for purposes of illustration, but it will be apparent that various other forms of rail fastenings are applicable to the situation.

It is understood that a cement bond is also provided before the slab is laid on the bottom 10d. Such slab is of a height even with the top of the rail, and its sides are spaced from the inner sides of the rails a sufficient distance to permit the flanges of the standard railway wheels to pass between.

It will be evident from the above description that I have provided a roadbed which serves in the nature of ties for the railway track, but is an improvement over the same by being continuous, so that no part of the track is unsupported. Further, the sides of the cavity for the track form a rigid and permanent abutment for the rails, so that these cannot spread at any time and render the travel of the rolling equipment unsafe. Further, the outer base flanges of the rails are seated in grooves carried by the said sides, so as to preclude all twisting or angular deviation of the rails from shock or stress. Further, the inner base flanges of the rails are positively locked from departure by abutting the side faces of the spacing slab 15. Yet, this slab is sufficiently spaced from the head 12 of the rails to permit the flanges of the car wheels to

travel therebetween. The slab 15 itself is also locked from lateral deviation by seating in the depressed portion of the roadbed afforded by the sleeves 10c. Further, the sections of the roadbed are joined in a longitudinal series by the periodical cross-members and are prevented from lateral movement by the terminal projections or stops of such cross-members. Altogether, the novel roadbed is safe in preventing the wheels 16 of the rolling equipment from falling off the rails in case of a broken axle or other mishap; and the roadbed is at all times serviceable for a highway for all vehicular traffic, so that it may be so used in case overflow traffic space is required, as in the event of special or wartime transportation.

While I have described the invention along specific lines, various minor changes and refinements may be made therein from time to time 20 without departing from its principle, and I consider all such changes and refinements as coming within the scope and spirit of the appended claims.

I claim:—

1. A roadbed for railway tracks comprising a longitudinal series of concrete members serving as ties, and means to unite the members at the joints to form a continuous support for the tracks comprising abutting portions of said members transversely recessed from underneath to form a bottom channel along the line of the joint, and a cross member seating in said channel.

2. The structure of claim 1, and upward projections from the ends of the cross-member 35 alongside the joined members.

3. A roadbed for railway tracks comprising a concrete base longitudinally recessed in its upper surface, and supports adjoining the sides of the recess to seat the rails so that the outer 40 sides of the heads thereof abut the sides of the recess said supports being raised from the floor of said recess, and a filler slab seating on said floor of said recess between said supports, the outer ends of said slab being in substantially 45 abutting relation with the inner edges of said supports.

4. A roadbed for railway tracks comprising a concrete base longitudinally recessed in its upper surface, supports adjoining the sides of the 50 recess to seat the rails so that the outer sides of the heads thereof abut the sides of the recess, and a filler slab in said recess and filling the space between the inner base flanges of the rails.

5. The structure of claim 3, said supports being shelves inwardly directed from the sides of the recess and terminating evenly with the edges of the inner base flanges of the rails.

6. A roadbed for railway tracks comprising a concrete base longitudinally recessed in its upper 60 surface, supports adjoining the sides of the recess to seat the rails so that the outer sides of the heads thereof abut the sides of the recess, said supports being shelves stepped up from the bottom of the recess, securing means for each 65 rail directed into said bottom along the inner

sides of the rails to clamp the inner base flanges thereof to said shelves, and a filler slab seating on said bottom between the shelves, said slab being recessed from underneath to clear said securing means.

7. A roadbed for railway tracks comprising a concrete base longitudinally recessed in its upper surface, supports adjoining the sides of the recess to seat the rails so that the outer sides of the heads thereof abut the sides of the recess, 10 said supports being shelves stepped up from the bottom of the recess, securing means for each rail directed into said bottom along the inner sides of the rails to clamp the inner base flanges thereof to said shelves, and a longitudinal series 15 of filler slabs along the inner sides of the rails and seating on said bottom, said securing means occurring adjacent to the meeting lines of the slabs, and the latter being recessed from underneath in the zones of the securing means to accommodate the same.

8. The structure of claim 1, said continuous support being longitudinally recessed in its upper surface, supports adjacent the sides of the recess to seat the rails so that the outer sides of the 25 heads thereof abut the sides of the recess, said supports being shelves stepped up from the bottom of the recess, securing means for each rail directed into said bottom along the inner sides of the rails to clamp the inner base flanges thereof to said shelves, and a filler slab seating on said 30 bottom between the shelves, said slab being recessed from underneath to clear said securing means.

9. The structure of claim 1, said continuous support being longitudinally recessed in its upper surface, supports adjacent the sides of the recess to seat the rails so that the outer sides of the 35 heads thereof abut the sides of the recess, said supports being shelves stepped up from the bottom of the recess, securing means for each rail directed into said bottom along the inner sides of the rails to clamp the inner base flanges thereof to said shelves, and a longitudinal series 40 of filler slabs along the inner sides of the rails and seating on said bottom, said securing means occurring adjacent to the meeting lines of the slabs, and the latter being recessed from underneath in the zones of the securing means to 45 accommodate the same.

10. A roadbed for railway tracks, comprising a concrete base longitudinally recessed in its upper surface, said recess being of a size and shape to seat the rails so that the outer sides of the heads thereof abut the sides of the recess, and a filler 55 slab in said recess, the upper surface of said slab being flush with the upper surface of the rail heads, the end surfaces of said slab being in abutting relation with the inner edges of the inner base flanges of said rails to maintain said rails in position in said recess and provide a groove above the base flange between the inner side surfaces of the rail heads and webs and the end surfaces of said slab.
